UNITED STATES PATENT OFFICE

FREDERICK A. SCHLOSSOW, OF DETROIT, MICHIGAN

TOILET BOWL

Application filed July 2, 1930. Serial No. 465,340.

My invention relates to toilet bowls shown in the accompanying drawings and more particularly pointed out in the following specification and claims.

Manufacturers of bath room equipment have for years been engaged in the endeavor to produce a closet bowl in which the noise resulting from flushing the bowl is eliminated and while some progress in that direction 10 has been made—so called “quiet” bowls now on the market are far from being noiseless.

The primary object of the present invention is to provide a bowl in which the air normally entrained in the flushing rim is not expelled with the water into the bowl, 15 thus eliminating the noise that would otherwise follow.

A further object of the invention is to provide a construction which will insure a 20 quick, positive siphonage of the bowl without any possibility of the water backing up into the bowl after siphonage has once been established.

With the foregoing and other objects in 25 view which will appear as the description proceeds, the invention further resides in the combination and arrangement of parts and in the details of construction hereinafter described and claimed, it being understood that 30 changes may be made in the precise embodiment of the invention herein disclosed without departing from the spirit of the same.

In the drawings accompanying this specification:

35 Figure 1 is a vertical longitudinal sectional view through the bowl, with parts broken away to more clearly disclose the construction.

Figure 2 is a plan and horizontal sectional 40 view taken on or about line 2—2 of Figure 1.

Figure 3 is a side elevation with parts broken away and in section showing the jet-duct leading from the water inlet to the jet well, also in dotted lines a valve controlling 45 the delivery of water to the bowl from a water main.

Figure 4 is a vertical cross-sectional view through the bowl, taken on or about line 4—4 of Figure 3.

50 Figure 5 is a fragmentary view of a detail

of construction, partly in section, taken on or about line 5—5 of Figures 1 and 2.

Referring now to the letters of reference placed upon the drawings:

A denotes the closet bowl in its entirety. 55

B indicates a valve controlling the delivery of water from a source of supply into a chamber C from which it passes through a duct D into the flushing rim D¹ and thence through a plurality of discharge ports D² below the rim with openings directed toward the wall of the bowl to provide a suitable wash-down. One of these discharge ports (D²) is relatively larger than the others, the purpose of which will be hereafter explained. 60 65

Extending downwardly from the chamber C on opposite sides of the bowl and formed in the outer walls of the latter are a pair of jet ducts E, E—see Figures 2 and 3, also in dotted lines in Figure 4,—into a pair of transversely extending channels E¹, E¹ opening into a jet wall E^a. 70

F denotes the up-leg of the siphon, G the down-leg of the siphon and H the outlet of the siphon, the respective ducts F, G and H forming together what is known in the art as a siphon trap. 75

I is an auxiliary water chamber connected with the flushing rim D¹ by a duct I^a.

J denotes a conduit extending through the jet well E^a, for connecting the auxiliary water chamber I with the lower, or submerged portion of the bowl, it being noted that the water in the lower part of the jet well E^a is free to pass around the conduit J into the upper portion of the jet well, see Figures 1 and 4. 80 85

K indicates a port or jet opening from the upper end of the jet well E^a into the bowl and L a port leading from the lower end of the jet well into the bowl and in axial alignment 90 with the up-leg F of the siphon-trap.

L^a denotes the normal water level in the bowl and M^a the water line in bowl when siphonage occurs.

The flushing rim is divided at the front of 95 the bowl by two partitions D^a, D^a spaced apart—see Figures 2 and 5, with a port D^b, D^b extending through the upper portion of each wall thereby forming a “pocket” D^c below the ports D^b, which may or may not be pro- 100

vided with an outlet D^a discharging against the inner wall of the bowl,— see Figures 1 and 5.

It will be noted that the duct I^a , leading to 5 the auxiliary water chamber I opens into the pocket formed between the partitions D^a , D^b ,— see Figures 2 and 5.

The horizontal discharge ports D^2 extending 10 through the crenelated lower wall of the flushing rim are directed at a tangent to the curved surface of the bowl and serve to effect a whirling motion of the water and thereby hasten a thorough scrubbing of the surface of the bowl as it is discharged.

15 Having indicated the several parts by reference letters, the construction and operation of the device will be readily understood.

Water is admitted to the chamber C by the manual operation of the valve B, a portion of 20 which passes through the port D into the flushing rim D^1 . The remainder of the water passes through the jet ducts E, E into the opposing transversely extending channels emptying into the jet well E^a and thence into the 25 bowl through the ports K and L.

A portion of the water entering the flushing rim passes to the bowl through the ports D^2 and D^3 while the remainder flows through ports D^b D^b into the pocket D^e thence through 30 duct I^a into the auxiliary water chamber I, thence through conduit J into the bowl. A portion of the water in the pocket D^e may also pass through the outlet D^a against the inner wall of the bowl.

35 All the air contained within the flushing rim or that entering the rim from the chamber C is carried through ports D^b D^b into the water chamber I, where it remains until the flush is terminated, when the chamber 40 fills with water to the normal water level L^a .

This eliminates the noise present when the air is expelled through the flushing rim ports into the bowl.

The rim ports D^2 and D^3 are designed to 45 direct the water against the inner surface of the bowl at an angle which will cause the water to spread evenly over the entire area of the bowl and also impart a whirling motion to the water therein. Discharge port D^3 admits a larger volume of water than the ports 50 D^2 and thereby forces up a wave of water at the front of the bowl which flows downwardly in such manner as to assist in washing foreign matter toward the entrance to the 55 up-leg F, of the siphon-trap.

Jets of water, at predetermined and varying angles are directed into the up-leg F of the siphon-trap through ports J, K and L to accelerate the flow of water through the trap, 60 thereby hastening the moment of siphonic action in the trap.

The described combined whirling and jet enforced movement quickly induces a siphonic action sufficient to lower the central portion of the water within the bowl to the line

65 M^a or slightly below the latter, thereby drawing foreign matter into the trap.

The port or jet K, which may be multiple, 70 prevents eddies from forming at or near the entrance to the trap, and assists in washing foreign matter into the latter.

The conduit J is directed toward the top 75 wall of the up-leg F of the siphon trap and prevents eddies or pockets forming at the entrance of the up-leg,—a common occurrence in bowls wherein a considerable volume of air enters the trap at that point.

Having thus described my invention, what I claim is:

1. In a toilet bowl; a valvecontrolled chamber adapted for connection with a source of water supply; a rim channel encircling the bowl and connected with the chamber having a plurality of outlets for the discharge of water against the inner face of the bowl, 85 said channel being adapted to deliver air entrained with the water into a body of water previously delivered to the bowl, whereby noises due to the escape of air are eliminated; tortuous passages forming a siphon trap with 90 an inlet from the bowl and a discharge outlet for connection with a soil pipe; a water chamber located below the rim channel connected therewith by a duct for the passage of air and water into said water chamber; ducts 95 leading downwardly from the valve controlled inlet water chamber to a jet well having a lower port opening directed into the bowl at the opening into the siphon trap; and a conduit extending through the jet well connecting the water chamber below the rim channel with the bowl, adjacent the lower port opening of the jet well, said jet well having also a port opening into the bowl above the conduit opening into the latter. 100

2. In a toilet bowl, a valve controlled water chamber adapted for connection with a source of water supply, a rim channel encircling the bowl connected with the water chamber, having a plurality of horizontally directed outlets for the discharge of the water tangentially against the inner surface of the bowl; 110 a pair of spaced transverse partition walls dividing said rim channel, forming a pocket with openings through the top of the walls for the passage of air and water; a water chamber located below the rim channel and connected with the pocket in the latter for the passage of water and entrained air into the last named water chamber; a tortuous passage 115 forming a siphon trap with an inlet from the bowl, and a discharge outlet for connection with a soil pipe; ducts leading downwardly from the valve-controlled water chamber to a jet well, having a lower port opening directed into the bowl at the opening into the siphon-trap, also an upper port opening through the wall of the jet well adjacent the water level in the bowl when siphonage occurs; and a conduit extending 120

through said jet well between its upper and lower port openings connecting the water chamber with the bowl.

3. In a toilet bowl, a chamber adapted for connection with a source of water supply; an inwardly overhanging rim channel encircling the bowl, having a crenelated lower wall jutting downwardly from the rim provided with substantially horizontal discharge ports adapted to direct the flow of water tangentially over the surface of the bowl below the overhanging rim; an auxiliary water chamber including a conduit adapted to discharge into the basin of the bowl; a passage originating at the top of the rim channel adapted to convey air displaced by flushing water from said channel into said auxiliary chamber, whereby noise due to the escape of entrained air through the rim channel outlets is eliminated.

4. In a toilet bowl, a chamber adapted for connection with a source of water supply; an inwardly overhanging rim channel encircling the bowl, having a crenelated lower wall jutting downwardly from the rim provided with substantially horizontal discharge ports adapted to direct the flow of water from the rim channel tangentially over the surface of the bowl below the overhanging rim; an auxiliary water chamber adapted to temporarily retain the air displaced from the rim channel by the incoming water; a passage adapted to convey the air from said rim channel into the auxiliary water chamber; a conduit adapted to discharge water from said auxiliary chamber into the basin of the bowl, whereby noise due to the escape of entrained air through the rim channel outlets is eliminated.

40 5. In a toilet bowl, a chamber adapted for connection with a source of water supply; an inwardly overhanging rim channel encircling the bowl, having a crenelated lower wall jutting downwardly from the rim provided with substantially horizontal discharge ports adapted to direct the flow of water tangentially over the surface of the bowl and below the overhanging rim; an auxiliary water chamber; a passage adapted to convey displaced air from the top of the rim channel to said auxiliary water chamber; a conduit connecting said auxiliary water chamber with the basin of the bowl, said conduit adapted to trap air within said auxiliary water chamber, whereby noise due to the escape of entrained air through the outlets integral with the hollow rim is eliminated.

60 6. In a toilet bowl, a chamber adapted for connection with a source of water supply; an inwardly overhanging rim channel encircling the bowl, having a crenelated lower wall jutting downwardly from the rim provided with substantially horizontal discharge ports, adapted to direct the flow of water tangentially over the surface of the

bowl and below the overhanging rim, an auxiliary water chamber; a passage adapted to convey displaced air from the top of the rim channel into said auxiliary water chamber; a conduit connecting said water chamber with the basin of the bowl, said conduit adapted to trap air within said water chamber, whereby noise due to the escape of entrained air through the outlets integral with the hollow rim is eliminated.

In testimony whereof, I sign this specification.

FREDERICK A. SCHLOSSOW.
